(57) **CLAIM**

The ornamental design for a jig for binding perforated sheets on a ring binder, as shown and described.

DESCRIPTION

FIG. 1 is a front perspective view of a jig for binding perforated sheets on a ring binder;
 FIG. 2 is a top view thereof;
 FIG. 3 is a bottom view thereof;
 FIG. 4 is a left-end view thereof;
 FIG. 5 is a right-end view thereof;
 FIG. 6 is a rear view thereof;
 FIG. 7 is a front view thereof; and,
 FIG. 8 is a front perspective view thereof with a handle in a raised position.
 The broken line showing is for illustrative purposes only and forms no part of the claimed design.
